UNITED STATES PATENT OFFICE.

CHARLES A. SHAFFER, OF PHILADELPHIA, PENNSYLVANIA.

SELF-PLAYING MUSICAL INSTRUMENT AND NOTE-SHEET THEREFOR.

SPECIFICATION forming part of Letters Patent No. 758,860, dated May 3, 1904.

Application filed July 21, 1903. Serial No. 166,450. (No model.)

To all whom it may concern:

Be it known that I, CHARLES A. SHAFFER, a citizen of the United States, residing at Philadelphia, county of Philadelphia, and State of Pennsylvania, have invented a new and useful Improvement in Self-Playing Musical Instruments and Note-Sheets Therefor, of which the following is a full, clear, and exact description, reference being had to the accompanying drawings, which form a part of this specification.

My invention relates to self-playing musical instruments.

The objects of the invention are to automatically operate the keys or strings of a musical instrument, to stop the travel of the music-sheet at the end of a tune, and to automatically rewind the music-sheet at the end of its forward movement.

The invention consists in the music-sheet, fingers contacting therewith, key-actuating devices, feeding mechanism, stopping mechanism, reversing mechanism, and electric devices and circuits controlled by the music-sheet and controlling the key-actuating device and feeding, reversing, and stopping mechanism constructed, arranged, and combined as hereinafter described and claimed.

In the drawings, Figure 1 is a plan view of the instrument. Fig. 2 is a section on the line 2 2 of Fig. 1. Fig. 3 is a section on the line 3 3 of Fig. 1. Fig. 4 is a plan view of the fingers engaging the under side of the note-sheet. Fig. 5 is a diagrammatic view showing the electrical connections. Fig. 6 is an enlarged transverse sectional view of the note-sheet. Figs. 7 and 8 are respectively top and bottom plan views of the note-sheet.

a is the music or note sheet. The same consists of a body of metal, such as copper, having an insulated surface *a'* on both sides. This insulated surface may be formed by coating the metal with a liquid non-conducting solution which hardens on setting or cooling, for which purpose a tough or brittle gum or varnish may be employed. I have found that a solution of commercial French varnish and alcohol is excellently adapted to the purpose.

The insulated surface may also be formed by treating the metal body with an acid, causing the surface of the metal to corrode and rendering it non-conducting. The insulated surface may also be formed by attaching a sheet of insulating material to the metal body. The insulating-surface on one side is scraped or cut off, as shown in Figs. 6 and 7, to form the notes, these cut-away portions 1 corresponding to the perforations of an ordinary music-sheet. On the other side the insulating-surface is cut away to form one or more long continuous strips 2 2, a series of short cut-away portions 3 4 5, a cut-away portion 6 at one end of the end of the strip, and a cut-away portion 7 at the other end of the strip, all of which are adapted to be engaged by suitable fingers and to control the stopping and rewinding of the music-sheet as well as the operation of the keys or strings of the musical instrument, as will be fully described.

It will of course be understood that I do not limit myself to any particular way of forming the insulated or non-insulated portions of the sheet.

10 is the frame of the machine.

g is the removable music-sheet-holding spool or roll, and *h* the music-sheet receiving or take-up spool or roll. The roll *g*, on which the sheet is wound when off the machine, is removably held in place by the following means:

i is a shaft turning in a bearing on one side of the machine-frame.

j is a stud longitudinally slidable in a bearing in the opposite side of the machine-frame and normally pressed inwardly by means of a spring *k*. The shaft and stud each have a conical head adapted to engage a conical depression in the end and on the line of the axis of the holding-roll *g*. It will be understood that the roll *g* may be readily and quickly inserted by seating one end of the roll on the end of shaft *i* and then moving it into substantially its operative position, the stud *j* first yielding outwardly and then springing inwardly into its seat at the other end of the roll, thus centering the roll, as well as securely holding it in position.

The shaft *i* is driven by mechanism to be described, and its motion of rotation is imparted to the roll *g* by means of a projection *m* on the shaft engaging an orifice or slot *n* in the 5 roll.

The take-up roll *h* is held in place at the other end of the machine in the same way that the holding-roll *g* is held in place, *o* representing the driven shaft, *p* the stud, and *q* and *r*, 10 respectively, the projection and orifice for imparting the rotation of shaft *o* to the roll. As the take-up roll need not be removable, I prefer to provide the stud with a screw-thread and screw the stud through a screw-threaded orifice in the frame instead of having it, like stud *j*, work loosely in and out.

When the holding-roll is placed in position, the music-sheet thereon is partially unwound by hand and the ring *s* on the front end thereof 20 slipped over the hook *t* on the take-up roll. The shaft *o* is engaged with its driving mechanism and the shaft *i* disengaged from its driving mechanism (hereinafter fully described) and the music-sheet wound upon the 25 take-up roll *h* and unwound from the holding-roll *g*.

I will now describe the contact-fingers that engage the cut-away portions of the music-sheet hereinbefore described and the functions 30 performed by each set of perforations and the fingers corresponding thereto.

Pivotedly secured to the rear end of the machine is a finger-frame *u*, carrying the note-fingers *b*, there being one finger to each key 35 or string of the instrument to be operated. This frame may be uplifted on its pivot when access to the take-up roll is desired, as when securing the end of the music-sheet thereto. The cut-away portions 1 are of course arranged 40 like the perforations of an ordinary music-sheet, so that when any particular note is to be struck a cut-away portion on the sheet is arranged in line with the particular finger controlling the particular key or string adapted 45 when struck to produce that note. Each finger *b* is secured to the frame *u* near the latter's pivot and extends forwardly through an orifice in the bracket *v*, thence extending forwardly and downwardly through an orifice 50 near the extreme free end of the finger-frame. The fingers *b* are light and elastic and tend to press downwardly against the moving music-sheet, so as to make certain contact with the cut-away portions. Beneath the ends of the 55 fingers *b* the music-sheet passes over the smooth curved top of a cross-piece *w*, thus preventing any vertical oscillation of the sheet at the point where it is engaged by the fingers *b*.

c c are fingers secured to the cross-piece *w* 60 and extending upwardly and contacting with the long cut-away strips 2 2. The fingers *c* are electrically connected with a battery *x*. The fingers *b* are electrically connected with magnets *y*, there being one magnet for each

finger. The battery is electrically connected 65 with each magnet. When any finger *b* engages one of the cut-away portions 1, the battery-circuit is closed, the current passing from the battery to fingers *c*, thence through the metal body of the music-sheet, finger *b*, corresponding magnet *y*, and back to the battery. When any magnet is excited, it attracts 70 its armature, which is connected with one of the keys or strings of the instrument. The particular mechanism connecting the magnets 75 and the musical instrument to be operated is not shown, as it forms no part of my invention.

d is a finger secured to the cross-piece *w* and extending upwardly and contacting with the music-sheet and in line of travel of the cut-away portions 3, 4, and 5. A cut-away portion 3, 4, or 5 is provided at the end of the notes of a tune, and if there is more than one tune one of these cut-away portions is placed at the end of the notes of each tune. In the 85 drawings I have shown a sheet, partially broken away, that is supposed to contain the notes of three tunes, and three cut-away portions 3, 4, and 5 are therefore provided. The object of these cut-away portions is to stop 90 the machine at the end of each tune. To this end I provide in the circuit of the motor 8 a cut-out switch 9, forming the armature of a magnet *z*, one pole of the magnet being connected with the battery *x* and the other pole 95 with the finger *d*. When the finger *d* contacts with either of the cut-away portions 3, 4, and 5, the circuit is closed, the current passing from the battery *x* to fingers *c*, to strip 2, through the metal body of the music-sheet, to cut-away portion 3, 4, or 5, to finger *d*, to magnet *z*, and thence back to the battery *x*, thereby exciting the magnet *z* and opening the cut-out switch 9, thereby stopping the motor 8 and the machine. This feature is especially applicable to slot-machines, 100 in which the motor-circuit is automatically opened at the end of each tune. The machine is started by again closing the switch 9 by hand or by any well-known automatic mechanism, such as is employed in slot-machines. 105

e f are fingers secured to the cross-piece *w* and extending upwardly and contacting with the music-sheet and in line of travel of the cut-away portions 6 and 7, respectively, the 110 function and operation of which is hereinafter described.

The mechanism for operating the rolls *g* and *h* is as follows: 11 is the shaft of motor 8. 12 and 13 are pulleys on the motor-shaft. 14 is a tilting frame pivoted on the motor-shaft. 20 is a shaft journaled near one end of frame 14, said shaft carrying the pulley 21 and gear 22. 30 is a shaft journaled near the other end of frame 14, said shaft carrying the pulley 31 and gear 32. The pulley 21 is connected through a belt 23 with the pulley 12, and the pulley 31 is connected through a 125

belt 33 with the pulley 13, thereby constantly revolving the gears 22 and 32. 40 and 41 are two double magnets, one double magnet being in one circuit and the other double magnet in another circuit, as hereinafter described. The tilting frame 14 acts as the armature of these magnets, and dependent upon which pair of magnets is energized one or the other end of the tilting frame 14 is drawn down and the opposite end drawn up. In the drawings the end of the tilting frame carrying the shaft 30 is drawn down, thus holding the gear 32 in engagement with the gear 60 on the shaft *o*. When the opposite end of the tilting frame is drawn down, the gear 32 is moved out of engagement with the gear 60, and the gear 22 is moved into engagement with the gear 50 on the shaft *i*. It will be understood that by controlling the circuit to the magnets 40 and 41 either the holding-roll *g* or the take-up roll *h* may be actuated. To this end finger *e* is electrically connected with double magnet 40 and finger *f* with double magnet 41. When the music-sheet is nearly entirely unwound from the holding-roll *g* and the fingers *b* have passed over the last of the notes on the upper surface of the music-sheet, the finger *f* contacts with the cut-away portion 7 and the following circuit is established: from the battery to fingers *c*, cut-away strips 2 2, through the conducting-body of the music-sheet, to cut-away portion 7, finger *f*, magnet 40, and to the battery, thereby moving down the end of the tilting frame, carrying the shaft 20, moving gear 32 out of engagement with the gear 60, and moving gear 22 into engagement with the gear 50 on the shaft *i*, thereby imparting rotation to the holding-roll *g* and rewinding the music-sheet thereon. The rewinding continues until the music-sheet is nearly entirely unwound from the take-up roll *h*, whereupon the finger *e* contacts with the cut-away portion 6 and the following circuit is established: from the battery to fingers *c*, cut-away strips 2 2, through the conducting-body of the music-sheet to cut-away portion 6, finger *e* to magnet 41 and to the battery, thereby moving down the end of the tilting frame carrying the shaft 30, moving gear 22 out of engagement with the gear 50, and moving gear 32 into engagement with the gear 60 on the shaft *o*, thereby again imparting rotation to the take-up roll *h*. The music-sheet now again feeds forward a short distance until finger *d* contacts with the cut-away portion 5, thereby causing the motor-circuit-cut-out switch 9 to be opened and the machine to stop, as before described.

It will be observed that the sizes of pulleys 12, 13, 21, and 31 and gears 22, 32, 50, and 60 are so proportioned that the rewinding operation is a comparatively very rapid one.

In order to insure maintaining the tilting frame 14 in either of its two positions, I have

formed on one end thereof two notches 71 65 and 73, one or the other of which is adapted to be engaged by the cam-head of a spring 72, secured to the frame of the machine.

As the frame 14 is tilting to place the holding-roll into driven engagement an arm 80, 70 secured to the frame 14, engages the finger-frame *u* and raises it so as to raise the fingers *b* out of engagement with the music-sheet and hold them out of contact with the music-sheet until the latter is rewound. At the same time 75 the finger *d* is depressed out of engagement with the music-sheet by the following means: The end of the finger is curved to form a hook, through which extends a bar 81. 82 is a shaft pivoted in the side members of the 80 frame. 83 is a lever secured between its ends to the shaft 82 and connected by means of links 84 and 85 with one end of the bar 81 and the arm 80, respectively. 86 is a connection from the shaft 82 to the other end of the bar 85 81. As the arm 80 rises, through the mechanism just described, the flexible end of finger *d* is drawn down out of contact with the music-sheet.

I do not herein lay claim to the music-sheet 90 *per se*, as the same forms the subject-matter of a separate divisional application, Serial No. 184,395, filed December 9, 1903. So far as concerns the invention claimed herein I do not limit myself to a music-sheet having the 95 cut-away notes 1 on one side and the cut-away portions 2, 3, 4, 5, 6, and 7 on the other side, as specifically described. Any of the cut-away portions may be placed on either side or the sheet may be insulated on one side 100 only and all the cut-away portions arranged on that side; nor do I lay claim herein to the mechanical construction of the feeding, stopping, and reversing mechanisms, as the same forms the subject-matter of a separate 105 divisional application, Serial No. 184,394, filed December 9, 1903. So far as concerns the invention claimed herein the mechanical construction of these parts may be substantially 110 changed without departing from the invention claimed herein.

Having now fully described my invention, what I claim, and desire to protect by Letters Patent, is—

1. The combination, with a music-sheet consisting of a body of conducting material having an insulated surface on both sides, said insulation being cut away to form notes and also being cut away on one side to form a continuous contact-strip extending lengthwise of the sheet, of fingers engaging the notes, a finger constantly engaging the contact-strip during the playing operation, an electric circuit including said fingers, and a key-actuating device also included in said circuit. 115 120 125

2. The combination, with a music-sheet consisting of a body of conducting material having an insulated surface cut away to form one

- or more cut-away portions, of a finger *c* constantly engaging the conducting-body during the playing operation, a finger *d* engaging the insulated surface but in line of movement of said cut-away portion or portions, driving mechanism to feed said sheet, means controlling the stopping of the driving mechanism, an electric circuit including said fingers, and a device in said circuit adapted to actuate said 10 stop-controlling means.
3. The combination, with a music-sheet consisting of a body of conducting material having an insulated surface cut away to form one or more cut-away portions, of a finger *c* constantly engaging the conducting-body during the playing operation, a finger *d* engaging the insulated surface but in line of movement of said cut-away portion or portions, a motor, driving connections from the motor to the 15 sheet, an electric circuit including the motor, a switch in said circuit, a magnet in proximity to said switch, and an electric circuit including said magnet, the opposite poles of the magnet-circuit being connected respectively with said 20 fingers.
4. The combination, with a music-sheet consisting of a body of conducting material having an insulated surface cut away to form a contact-piece near one end of the sheet, of a finger *c* constantly engaging the conducting-body during the playing operation, a finger *e* engaging the insulated surface but in line of movement of said contact-piece, driving mechanism to feed said sheet, means connected 25 with the driving mechanism for reversing the direction of said feed, an electric circuit including said fingers, and a device in said circuit adapted to actuate said reversing means.
5. The combination, with a music-sheet consisting of a body of conducting material having an insulated surface cut away to form a contact-piece near one end of the sheet, of a finger *c* constantly engaging the conducting-body during the playing operation, a finger *e* 30 engaging the insulated surface but in line of movement of said contact-piece, a roll upon which said sheet is adapted to wind, a gear on the shaft of said roll, a motor, a tilting frame, a gear carried thereby, the last-named gear 35 being moved into or out of engagement with the first-named gear by the tilting of said frame in one direction or the other, a magnet adapted to tilt said frame, and an electric circuit including said magnet, the opposite poles 40 of said circuit being connected respectively with said fingers.
6. The combination, with a music-sheet consisting of a body of conducting material having an insulated surface cut away to form 45 notes, and one or more additional cut-away portions, of fingers *b* adapted to engage the notes, a finger *c* constantly engaging the conducting-body during the playing operation, a finger *d* in line of movement of the said ad- 50 ditional cut-away portion or portions, driving mechanism to feed said sheet, means controlling the stopping of the driving mechanism, an electric circuit including said fingers *b* and *c*, a key-actuating device included in said circuit, an electric circuit including said fingers *c* and *d*, and a device in the last-named circuit adapted to actuate said stop-controlling means. 55
7. The combination, with a music-sheet consisting of a body of conducting material having an insulated surface in which the insulation is cut away to form notes, and a contact-piece near one end of the sheet, of fingers *b* adapted to engage the notes, a finger *c* constantly engaging the conducting-body during the playing operation, and a finger *e* engaging the insulated surface but in line of travel of said contact-piece, driving mechanism to feed said sheet, means connected with the driving mechanism for reversing the direction of said feed, an electric circuit including said fingers *b* and *c*, a key-actuating device in said circuit, an electric circuit including said fingers *c* and *e*, and a device in the last-named circuit adapted to actuate said reversing means. 60
8. The combination, of a music-sheet consisting of a body of conducting material having an insulated surface cut away to form one or more cut-away portions, and a contact-piece near one end of the sheet, of fingers *d* and *e* engaging the insulated surface but in 65 line of travel respectively with the cut-away portions and the contact-piece, a finger *c* constantly engaging the conducting-body during the playing operation, driving mechanism to feed said sheet, means controlling the stopping of the driving mechanism, means connected with the driving mechanism for reversing the direction of said feed, an electric circuit including said fingers *c* and *d*, a device in said circuit adapted to actuate said stop-controlling means, an electric circuit including said fingers *c* and *e*, and a device in the last-named circuit adapted to actuate said reversing means. 70
9. The combination, with a music-sheet consisting of a body of conducting material having an insulated surface in which the insulation is cut away to form notes, a continuous contact-strip, one or more additional cut-away portions, and a contact-piece near one end of the sheet, of fingers *b* adapted to engage the notes, fingers *d* and *e* engaging the insulated surface but in line of travel respectively with the cut-away portions and the contact-piece, a finger *c* constantly engaging the continuous 75 strip during the playing operation, driving mechanism to feed said sheet, means controlling the stopping and starting of the driving mechanism, means connected with the driving mechanism for reversing the direction of said feed, an electric circuit including said fingers *b* and *c*, a key-actuating device in said circuit, a second electric circuit including said fingers 80

c and *d*, a device in said second circuit adapted to actuate said stopping and starting controlling means, a third electric circuit including said fingers *c* and *e*, and a device in the 5 last-named circuit adapted to actuate said reversing means.

In testimony of which invention I have here-

unto set my hand at Philadelphia on this 20th day of July, 1903.

CHARLES A. SHAFFER.
